ENGINE STARTER GEARING

Burr W. Jones, Elmira Heights, N. Y., assignor to
Bendix Aviation Corporation, South Bend, Ind.,
a corporation of Delaware

Application May 12, 1942, Serial No. 442,591

8 Claims. (Cl. 74—6)

The present invention relates to engine starter gearing and more particularly to that type in which a motor-driven pinion is manually operable into and out of engagement with a member of an engine to be started.

In manually shiftable starter gearing of the type which includes an overrunning connection for allowing the pinion to run ahead of the starting motor when the engine starts, considerable difficulty has been encountered in providing such structure which will drive reliably without slipping, and overrun without sticking.

It is an object of the present invention to provide a novel manually shiftable starter gear which is efficient and reliable in operation, small in size and economical in construction.

It is another object to provide such a device including an overrunning clutch engaging directly with the interior of the drive pinion and arranged to drive without undesirable slippage and to release without sticking.

It is a further object to provide such a device including an automatic self-tightening means for the overrunning clutch.

It is another object to provide such a device in which the clutch tightening means is in the line of transmission of torque from the starting motor to the clutch, whereby the pinion and clutch are free to overrun and release the clutch when the engine starts.

Further objects and advantages will be apparent from the following description taken in connection with the accompanying drawing in which:

Fig. 1 is a side elevation partly broken away and in section showing a preferred embodiment of the invention;

Fig. 2 is a similar view showing the parts in cranking position; and

Fig. 3 is a similar view showing the parts in the positions assumed in case of tooth abutment between the pinion and engine gear.

In Fig. 1 there is illustrated a power shaft 1 which may be the extended armature shaft of a starting motor not illustrated. The power shaft is provided with a smooth reduced extension 2 providing a shoulder 3, and a driving cam member 4 is mounted on said smooth portion with a thrust flange 5 engaging the shoulder 3 of the shaft and one or more driving lugs 6 seated in slots 7 in the power shaft and retained therein in any suitable manner as indicated at 8.

A split clutch sleeve 9 is loosely mounted on the smooth portion 2 of power shaft 1 and is provided with bevelled surfaces 11, 12, 13 and 14

adapted to be engaged by wedge-shaped projections 15 and 16 on a pair of expander members 17 and 18 respectively which are also slidably mounted on the portion 2 of the power shaft.

5 A pinion member 19 is slidably journaled on the clutch sleeve 9, expander members 15, 16 and driving cam member 4. The pinion member comprises a toothed portion 21 and an extended sleeve portion 22 which are rigidly connected together as by means of inter-engaging projections 23, 24 held in engagement by a lock ring 25, which is secured in position by a thrust collar 26, having a recess 27 closely surrounding the lock ring.

10 Manually operable means are provided for moving the pinion member 19 into and out of engagement with a member such as a gear 28 of an engine to be started. As here shown, this shifting means comprises a pivoted lever 29

15 which is arranged to be actuated by the operator in any preferred manner, the free end of which engages in a shift collar 31 slidably mounted on the sleeve 22 of the pinion member. A thrust spring 33 is located on the pinion sleeve 22,

20 bearing at one end against the interior of the shift collar 31 and at its other end against the thrust collar 26. The shift collar is retained on the pinion member by suitable means such as a lock ring 34.

25 Shift collar 31 is provided with inwardly projecting lugs 35 which pass through slots 36 in the pinion sleeve 22 so as to spline the shift collar to said sleeve, and bear freely on the extension 2 of the power shaft. A thimble 30 is slidably journaled on the smooth portion 2 of the power shaft within the pinion member sleeve 22

30 and acts as a spacer between the wedge member 18 and the lugs 35 of the shift collar as shown in Figs. 2 and 3.

35 Adjustable means such as indicated at 37 is provided for limiting the movement of the shift lever 29 toward operative position, and it will be understood that when the shift lever is moved to the limit of its travel as shown in Figs. 2 and

40 3, a switch will be closed to energize the starting motor in accordance with conventional practice in the manual shift type of electrical starting apparatus.

45 According to the present invention means responsive to rotation of the power shaft are provided for causing the wedge members 17 and 18 to expand the clutch sleeve 9 into gripping engagement with the interior of the pinion member and transmit rotation thereto. As here shown, this function is accomplished by the formation of

inter-engaging cam surfaces 38 and 39 on the driving member 4 and expanding member 17 respectively, such cam surfaces being so arranged that when the power shaft rotates the driving member 4 in the direction of the arrow, the expander member 17 is caused to move axially toward the expander member 18. Since at this time the expander member 18 is prevented from axial movement by the spacer thimble 30 abutting against the lugs 35 of the shift collar, the clutch sleeve 9 is wedged between the expander members as shown in Fig. 2.

In operation, starting with the parts in the positions illustrated in Fig. 1, movement of the shift lever 29 by the operator in the direction of the arrow causes the assembly including the shift collar 31, pinion member 19, and thimble 33 to slide longitudinally until the toothed portion 21 of the pinion member engages the engine gear 28 and abuts against the flange 5 of the driving member 4. Closure of the starting switch by the final movement of the shift lever causes rotation of the power shaft by the starting motor which rotation is imparted to the driving member 4. Members 17 and 18 are thus caused to wedge the clutch sleeve 9 into gripping engagement with the interior of the pinion member and transmit rotation thereto.

When the engine starts, the acceleration of the engine gear causes the pinion and its associated parts to overrun the driving member 4, thus relieving the wedging action of the expander members and permitting the clutch sleeve to contract and release the pinion member which thereupon overruns freely. When the operator returns the shift lever 29 to idle position, the pinion member and associated parts are withdrawn to their normal positions by means of the thrust ring 34 connecting the shift collar 31 to the pinion member.

If, during the meshing movement of the pinion, tooth abutment should occur between the pinion and engine gear as illustrated in Fig. 3, the spring 33 is arranged to yield sufficiently to permit the shift lever 29 to close the starting switch and actuate the clutch, whereupon rotation is transmitted to the pinion to index it into proper registry with the teeth of the engine gear. The spring 33 then expands and snaps the pinion into mesh with the engine gear and the cranking operation proceeds as described.

Although but one embodiment of the invention has been shown and described in detail, it will be understood that other embodiments are possible and that various changes in the design and arrangement of the parts may be made without departing from the spirit of the invention as defined in the claims appended hereto.

What is claimed is:

1. In an engine starter a power shaft, a driving member fixed thereon, an expansible sleeve on the power shaft, a pinion member slidably journaled on the driving member and sleeve, and means cooperating with the driving member to rotate the sleeve and expand it into clutching engagement with the interior of the pinion member.

2. In an engine starter a power shaft, a driving cam member fixed thereon, an expansible sleeve on the power shaft, a pinion member slidably journaled on the cam member and sleeve, manually operable shifting means for the pinion mem-

ber, an abutment member movable thereby, and means movable by the cam member cooperating with the abutment member to expand the sleeve into clutching engagement with the interior of the pinion member and transmit rotation thereto.

3. In an engine starter a power shaft, a split clutch sleeve loosely mounted thereon, a pinion member slidably journaled on the clutch sleeve, and means for expanding the sleeve into gripping engagement with the interior of the pinion member and for rotating the sleeve with the power shaft.

4. In an engine starter a power shaft, a split clutch sleeve loosely mounted thereon, a pinion member slidably journaled on the clutch sleeve, and means responsive to rotation of the power shaft for expanding the sleeve into gripping engagement with the interior of the pinion member and for rotating the sleeve with the power shaft, said means being arranged to release the clutch sleeve from the pinion when the pinion overruns the power shaft.

5. In an engine starter a power shaft, a split clutch sleeve loosely mounted thereon, a pinion member slidably journaled on the clutch sleeve, a pair of longitudinally movable expanding members for the sleeve, manually operable abutment means for one expander member, and means responsive to rotation of the power shaft for actuating the other expander member.

6. In an engine starter a power shaft, a split clutch sleeve loosely mounted thereon, a pinion member slidably journaled on the clutch sleeve, a pair of longitudinally movable expanding members for the sleeve, manually operable means for shifting the pinion into engagement with a member of an engine to be started, and providing an abutment for one of the expanding members, and a cam member fixed on the power shaft for actuating and rotating the other expanding member.

7. In an engine starter drive a power shaft, a clutch member loosely mounted thereon, a pinion member slidably journaled on the power shaft, a pair of members journaled on the power shaft operative by longitudinal movement to actuate the clutch member to engage and drive the pinion member, manually operable means for shifting the pinion member into engagement with a member of an engine to be started and providing an abutment for one of the clutch actuating members, and a cam member fixed on the power shaft for moving longitudinally and rotating the other clutch actuating member.

8. In an engine starter a power shaft, a pinion member, manually operable means for shifting the pinion member longitudinally into and out of engagement with a member of an engine to be started, and an overrunning clutch drive for the pinion member including a split clutch sleeve within the pinion member, an abutment member held against one end of the sleeve by the shifting member when the pinion is in operative position, a wedge member engaging the opposite end of the sleeve, and means responsive to rotation of the power shaft for moving the wedge member to press the sleeve against the abutment member and thereby expand it into frictional engagement with the pinion member.

BURR W. JONES.
